UNITED STATES PATENT OFFICE.

ALFRED MARCHEV, OF CICERO, ILLINOIS, ASSIGNOR TO WESTERN ELECTRIC COMPANY, INCORPORATED, OF NEW YORK, N. Y., A CORPORATION OF NEW YORK.

MATERIAL-HANDLING APPARATUS.

Application filed December 29, 1924. Serial No. 758,787.

This invention relates to material handling apparatus, and more particularly to mechanism for controlling the speed thereof.

The primary object of the invention is to provide, in a material handling apparatus, an improved mechanism whereby the operating speed is directly controlled by the character of the material being handled.

Other objects and advantages will become apparent in the following detail description, and the novel features of the invention will be particularly pointed out in the appended claims.

In accordance with the general features of the invention as herein disclosed, the air wiping die of a cable painting machine such as disclosed in the patent of Frederic S. Kochendorfer and Helmer J. Boe, No. 1,526,071, issued February 10, 1925, is provided with an elongated shank or stud whose length varies for various sizes and type of cables. When the die is mounted in its operative position, the end of the shank engages one end of a pivoted member which carries, at its opposite end, a plurality of electrical contact members adapted to establish either of a plurality of electrical circuits which control the speed of the driving motor.

In the accompanying drawings which illustrate one specific embodiment of the invention,

Fig. 1 is a side elevation of a cable painting machine embodying the features of the present invention;

Fig. 2 is an enlarged fragmentary vertical section of a portion of the paint container showing the air wiping die and the associated speed control mechanism;

Fig. 3 is a fragmentary plan section taken on the line 3-3 of Fig. 2;

Fig. 4 is a fragmentary plan section taken on the line 4-4 of Fig. 2, and

Fig. 5 shows a wiring diagram for the improved speed control mechanism including the windings of the driving motor.

Referring now to the drawings in detail wherein like reference characters designate like parts throughout the several views, 15 indicates the base or supporting member of a cable painting machine such as disclosed in the above mentioned patent. Positioned at one end of the base member 15 is an electric driving motor 16 which is controlled by an operating switch 14 positioned within con-

venient reach of the operator. Supported at the opposite end of the base member 15 is a paint container 17. Directly connected to the motor 16 is a main driving shaft 18 to which is secured a bevel pinion 33 which meshes with a bevel gear 34 secured to a vertically disposed shaft 35 (Fig. 1).

Secured at the lower end of the shaft 35 is a bevel pinion 36 which meshes with a bevel gear 37 secured to a horizontal shaft 38. A gear 40 is keyed to the shaft 38 and meshes with gears 41 and 42 positioned at either side thereof and secured to shafts or reel spindles 43 and 44, respectively. Reels 72, 72, are suitably mounted on the spindles 43 and 44 and may be used interchangeably as supply or take-up reels through mechanism disclosed in the above mentioned patent.

A plurality of grooved pulleys 115, 115 rotatably supported in suitable bearings serve to guide the cable in its travel from the supply reel 72 into the paint container 17, wherein it receives a coating of paint, and then to the take-up reel 72. After passing around the guide pulleys 115 mounted at the bottom of the paint container 17, the cable passes through an air wiping die 120 positioned near the top of the container, which serves to remove the surplus paint from the cable before being wound on the takeup reel. The air wiper 120 is connected to a compressed air line 122 which is controlled by a valve 123. Secured to the container 17 is a bracket or support 124 provided with a depression 125 for the reception of the wiper 120 (Fig. 2).

The air wiping die 120 is fully described in the above mentioned patent, and accordingly, a detailed description herein of the die, aside from the portion thereof which forms the subject-matter of the present application, is thought unnecessary.

The air line 122 is connected with a passage 134 in the bracket 124, which in turn 100 is connected with a passage 138 in the air wiping die 120. Formed in the die 120 at right angles to the passage 138 and connecting therewith are passages 141 and 142 (Fig. 4). A vertical passage 145 is provided 105 through the center of the die 120, and midway between the passages 141 and 142, to permit the passage of the cable therethrough. In the drawing, a flat type switchboard cable 109 has been shown and the passage 145 has 110

- a cross-section similar to that of the cable, but is slightly larger than the cable so that a suitable space is allowed between the surface of the cable and the wall of the passage 5 145 to permit the removed surplus paint to flow freely back into the container 17. If a cable which is circular in cross-section is to be operated upon, the passage 145 will be circular to correspond. Connecting the passage 145 with the passages 141 and 142 are a plurality of comparatively fine passages 146 which are formed at such an angle to the passage 145 that all are directed at the passing cable.
- 15 Suitably attached to the wiping die 120 is a stud or shank 132 which passes through an aperture 147 in the bracket 124 and through an opening 148 in the side of the container 17. The die 120 and its shank 132 are securely held in place by a set screw 160 which is threaded through the bracket 124 and is adapted to engage an aperture 161 formed in the shank 132. The end of the shank 132 protruding from the side of the container 17 engages one end 163 of a pivoted member 164 which is pivoted intermediate its ends at 165, and is inclosed within a housing 166 suitably secured to the container 17. The other end of the member 164 is 20 bifurcated and terminates in two legs 187 and 188. Electrical contact members 167, 168, and 169 are carried by the leg 187 and an electrical contact member 189 is carried by the leg 188 (Fig. 3). Mounted within the 25 housing 166 and positioned to be engaged by either the contact member 189 or the contact members 167, 168, and 169 are three contacts 170, 171, and 172 which are connected with the low speed terminals 180, 181, and 182 of the motor 16 (Fig. 5). Contacts 173, 30 174, and 175 which are connected with the high speed terminals 183, 184, and 185 of the motor 16 are also mounted within the housing 166 and are positioned to be engaged by the contact members 167, 168, and 169 when the member 164 is moved to a predetermined 35 position. Positioned intermediate the low speed contacts 170, 171, and 172 and the high speed contacts 173, 174, and 175 are three 40 electrical contacts 176, 177, and 178 which are connected with any suitable source of power, such as a generator 190 indicated conventionally in Fig. 5.
- When it is desired to operate the driving 45 motor at a low speed, the shank 132 of the air wiping die 120 is of such a length that when mounted in its operative position, the member 164 is displaced on its pivot 165 so that the contact members 167, 168, and 169 50 bridge the low speed contacts 170, 171, and 172 with the line contacts 176, 177, and 178, respectively (Fig. 3). A tension spring 179, mounted within the housing 166 serves to urge the end 163 of the member 164 against 55 the end of the die shank 132. In order to run the driving motor at high speed, which is desirable for certain types and sizes of cable, the air wiping die is provided with a slightly shorter shank thereby allowing the member 164 to assume the dotted position 70 shown in Fig. 3, wherein the low speed contacts 170, 171, and 172 are bridged by the contact member 189 and the high speed contacts 173, 174, and 175 are bridged with the line contacts 176, 177, and 178, respectively, 75 by the contact members 167, 168, and 169.
- In operating the above described apparatus, after the proper air wiping die has been mounted in position, it is only necessary for the operator to use the switch 14, 80 the proper driving speed being automatically selected by means of the length of the die shank 132.
- What is claimed is:
1. In a strand treating apparatus, a receptacle containing a treating bath, means for advancing a strand through said treating bath, an air wiping die having a predetermined characteristic supported in the path of movement of said strand and effective for removing the surplus treating material therefrom, and mechanism responsive in accordance with the predetermined characteristic of the supported wiping die for controlling the operation of said strand advancing means.
  2. In a strand treating apparatus, a receptacle containing a treating bath, electrically operated means for advancing the strand through said treating bath, an air wiping die having a predetermined characteristic supported in the path of movement of the strand and effective for removing the surplus treating material therefrom, mechanism comprising a plurality of contacts, and a contact arm cooperating with said contacts and adapted to be positioned with respect to said contacts in accordance with the predetermined characteristic of said die member whereby the operating conditions of said advancing means is controlled accordingly.
  3. In a material handling apparatus, a material treating member having an orifice, an element of predetermined length projecting therefrom, means for advancing the material through the orifice in said treating member, and means actuated in accordance with the predetermined length of said element for determining the speed of said advancing means.
  4. In a strand treating apparatus, a receptacle containing a treating bath, electrically operated means for advancing a strand through said bath, a material treating die having an element of predetermined dimension projecting therefrom, and a control mechanism comprising a plurality of contacts and a contact arm cooperating with the contacts, said arm designed to be positioned with respect to the contact members in ac-

- cordance with the predetermined dimension of the projecting element whereby the operating conditions of the advancing means are controlled.
5. In a material treating apparatus, material advancing means, means for controlling the operation of the advancing means including an oscillatable control arm, and an element of predetermined dimension supported in the apparatus so as to coact with the oscillatable control arm and to position the arm whereby the operation of the advancing means is controlled.
10. In a strand treating apparatus, a receptacle containing a treating bath, means for advancing a strand through the bath, means for controlling the operation of the advancing means including a contact arm, and an element of predetermined length supported in the apparatus so as to coact with
- the contact arm and to position the arm whereby the operation of the advancing means is controlled.
7. In a strand treating apparatus, a receptacle containing a treating bath, electrical means for advancing a strand through the bath, a mechanism for controlling the advancing means including a plurality of contacts and a contact arm cooperating with the contacts, and an element of predetermined length supported in the apparatus so as to coact with the contact arm and to position the arm with respect to the contacts whereby the operation of the strand advancing means is controlled.
15. In a strand treating apparatus, a receptacle containing a treating bath, means for advancing a strand through the bath, means for controlling the operation of the advancing means including a contact arm, and an element of predetermined length supported in the apparatus so as to coact with
- the contact arm and to position the arm whereby the operation of the advancing means is controlled.
20. In a strand treating apparatus, a receptacle containing a treating bath, means for advancing a strand through the bath, means for controlling the operation of the advancing means including a contact arm, and an element of predetermined length supported in the apparatus so as to coact with

In witness whereof, I hereunto subscribe my name this 18th day of December A. D., 1924.

ALFRED MARCHEV.
